(57) **CLAIM**

The ornamental design for a lamp, as shown and described.

DESCRIPTION

FIG. 1 is a perspective view of a lamp showing our new design having additional broken line environment included for contextual clarity.

FIG. 2 shows a top plan view of the lamp.

FIG. 3 shows a bottom plan view of the lamp.

FIG. 4 shows a front elevation view of the lamp.

FIG. 5 shows a rear elevation view of the lamp.

FIG. 6 shows a left side elevation view of the lamp.

FIG. 7 shows a right side elevation view of the lamp; and, FIG. 8 shows an exploded perspective view of the lamp with additional broken line environment in FIG. 1.

The broken lines shown in the drawings depict portions of the lamp that form no part of the claimed design. The broken lines showing light bulbs represent environment and form no part of the claimed design. The wavy broken line represents a terminal boundary of the claim and forms no part of the claimed design. The dash-dot-dash broken lines in FIG. 8 represent the connection of parts in expanded view and form no part of the claimed design.

1 Claim, 5 Drawing Sheets
